CARRIER-SIGNAL FREQUENCY-DETECTOR
SYSTEMHarold A. Wheeler, Great Neck, N. Y., assignor to
Hazeltine Corporation, a corporation of Delaware

Application August 12, 1940, Serial No. 352,211

8 Claims. (Cl. 250—27)

The present invention relates to an improved frequency detector system for carrier-signal receivers and, particularly, to such a system, the output of which varies in substantially linear relation over a predetermined frequency range with the frequency of a carrier signal applied thereto. While the invention is of general application, it has particular utility as the frequency detector system of a frequency-modulated carrier-signal receiver. The invention, therefore, will be described in connection with a frequency-modulated carrier-signal receiver wherein the invention is used to aid in obtaining freedom from distortion in the demodulation of the carrier signal over a much greater range of carrier-frequency deviation than has heretofore been attainable.

Frequency modulation, as distinguished from amplitude modulation, of a carrier signal has certain advantages under some conditions of reception, among which is the reduction of objectionable interference which may be caused either by background noise or by an undesired station transmitting on the same or a nearby carrier frequency. For satisfactory reception of a frequency-modulated carrier signal, however, a detector having a substantially linear frequency-response characteristic over a predetermined deviation range of a received carrier signal is essential. Furthermore, from the standpoint of sensitivity, it is desirable that the characteristic curve of the detector should have a slope as great as possible over its linear range.

The ideal detector for frequency modulation is one which not only faithfully reproduces the true form of the frequency-modulation components but also is unresponsive to amplitude fluctuations of the carrier signal. It has been proposed to reduce the effect of such amplitude fluctuations of the carrier signal by the use of a balanced frequency detector comprising a frequency-responsive network coupled to two rectifier devices which convert the frequency-modulation components into amplitude-modulation components of opposite polarities, and an arrangement for differentially combining the outputs of the two rectifiers to derive the frequency-modulation components free of any amplitude fluctuation disturbances.

Certain prior art balanced frequency detectors of this nature have employed a pair of signal-translating channels, each including an individual frequency-selective network, the frequency-transfer characteristic of which is linear over a predetermined frequency range, and indi-

vidual rectifiers having input-output transfer characteristics which similarly follow a substantially linear relation. Each of the frequency-responsive networks has been designed to have a frequency-response characteristic of slope opposite to that of the other over the range of carrier frequencies applied thereto and to have substantially zero response at one frequency, maximum response at another frequency, and substantially linear response between these two frequencies. The use of linear rectifiers with networks of this nature has required that the points of zero and maximum response both lie outside of the range of frequencies of the modulated carrier, since the combined output of the detectors is undistorted only so long as this is true. This not only has reduced the permissible range of carrier-signal frequencies but also has reduced the slope of the characteristic curve of the detector, thereby reducing its sensitivity.

It is an object of the invention, therefore, to provide an improved frequency detector system which, while of general application, is especially suitable for use in a frequency-modulated carrier-signal receiver and one which avoids one or more of the above-mentioned disadvantages and limitations of the prior art devices.

It is a further object of the invention to provide an improved frequency detector system including a pair of frequency-selective networks which has a linear output characteristic over a relatively wide range of carrier-signal frequencies applied to the input of the system and one in which the range of carrier-signal frequencies may include the frequencies of minimum response of the frequency-selective networks of the system.

It is an additional object of the invention to provide an improved frequency detector system which includes a balanced pair of output circuits, the output of each of which varies in a substantially parabolic relation with the frequency of a carrier signal applied to the system, whereby the differential of the outputs varies in substantially linear relation with the frequency of the carrier signal.

In accordance with the invention, a carrier-signal frequency detector system comprises a frequency-selective stage responsive to a predetermined range of frequency deviation of a carrier signal applied thereto and including a pair of impedance networks having predetermined frequency-transfer characteristics of the same type but sloping in opposite senses with frequency over a smaller frequency range lying within and

symmetrically positioned with respect to the mean frequency of such predetermined range. The networks individually have minimum responses at opposite edges of the aforesaid smaller frequency range. There is also provided a rectifier stage including a pair of rectifiers individually coupled to the impedance networks, the rectifiers having similar predetermined input-output transfer characteristics. The transfer characteristics of either the frequency-selective stage or the rectifier stage follows substantially a linear relation and that of the other stage follows a substantially square-law relation. The detector system has an output circuit including means for differentially combining the outputs of the rectifiers to derive an output having substantially linear variation with frequency over a range of frequency deviation including said predetermined range.

For a better understanding of the present invention, together with other and further objects thereof, reference is had to the following description, taken in connection with the accompanying drawing, and its scope will be pointed out in the appended claims.

Referring now to the drawing, Fig. 1 is a circuit diagram, partly schematic, of a complete frequency-modulated carrier-signal receiver embodying the invention; Fig. 2 comprises a number of graphs representing the frequency-response characteristics of the frequency-selective stage, the rectifier stage, and the differential output of the detector system of the Fig. 1 arrangement; and Fig. 3 is a partial circuit diagram, partly schematic, of a modification of the frequency detector system of the invention.

Referring now more particularly to Fig. 1, there is represented schematically a complete frequency-modulation carrier-signal receiver of a conventional design embodying the present invention in a preferred form. In general, the receiver includes a radio-frequency amplifier 10 having its input circuit connected to an antenna system 11, 12 and having its output circuit connected to an oscillator-modulator 13. Connected in cascade with the oscillator-modulator 13, in the order named, are an intermediate-frequency amplifier 14 of one or more stages, an additional stage of intermediate-frequency amplification 15, a frequency detector system 16, 17, more fully described hereinafter, an audio-frequency amplifier 18 of one or more stages, and a sound reproducer 19. An automatic amplification control or A. V. C. rectifier 20 also is connected to the intermediate-frequency amplifier 14 and the output of the rectifier is applied in conventional manner over the conductor indicated as A. V. C. to the input circuits of one or more of the tubes of the radio-frequency amplifier 10, the oscillator-modulator 13, and the intermediate-frequency amplifier 14.

It will be understood that the various units just described may, with the exception of the frequency detector system 16, 17, be of a conventional construction and operation, the details of which are well known in the art, rendering detailed description thereof unnecessary. Considering briefly the operation of the receiver as a whole, and neglecting for the moment the detailed operation of the frequency detector system 16, 17 presently to be described, a desired frequency-modulated carrier signal is selected and amplified by the radio-frequency amplifier 10, converted to a frequency-modulated intermediate-

frequency carrier signal in the oscillator-modulator 13, amplified in the intermediate-frequency amplifiers 14 and 15, and detected by the frequency detector system 16, 17, thereby to derive the audio-frequency modulation components. The audio-frequency components are, in turn, amplified in the audio-frequency amplifier 18 and are reproduced by the sound reproducer 19 in a conventional manner.

The intermediate-frequency carrier signals also are applied to the automatic amplification control or A. V. C. rectifier 20 to derive an automatic control or A. V. C. bias. This bias is effective to control the amplification of one or more of the units 10, 13, and 14 to maintain the signal input to the frequency detector 16, 17 within a relatively narrow range for a wide range of received signal intensities.

Referring now more particularly to the portion of the system embodying the present invention, the output of the intermediate-frequency amplifier 14 is applied to an additional stage of intermediate-frequency amplification 15 which, if desired, may be so biased as to operate with limiting action to limit to a predetermined amplitude level carrier signals translated by this amplifier stage. The amplifier 15 comprises a pair of vacuum tubes 21, 22, the output circuits of which include load impedances 23, 24, respectively. The carrier signals developed across these load impedances are of opposing phase but of equal intensity and are, therefore, balanced voltages with respect to ground. These signals are applied through coupling condensers 25, 26 to a frequency-selective stage 16 responsive over a predetermined range of frequency deviation of the carrier signals applied thereto and including a pair of impedance networks 27, 28. The impedance network 27 includes an inductor 29 shunt-tuned by a condenser 30 and a series-resonant shunt trap circuit comprising an inductor 31 and a condenser 32. Similarly, the impedance network 28 has an inductor 33 shunt-tuned by a condenser 34 and a series-tuned shunt trap circuit comprising an inductor 35 and a condenser 36. The manner of tuning the resonant circuits of the networks 27 and 28 will be described in greater detail hereinafter.

The output of the frequency-selective stage 16 is applied to a rectifier stage 17 which includes a pair of pentode vacuum tubes 37, 38 biased near cutoff to operate as anode-circuit rectifiers for detecting amplitude variations. The output circuits of detectors 37, 38 include respective halves 39a, 39b of the primary winding of an audio-frequency transformer 40. Condensers 41 and 42 are provided to by-pass carrier-frequency currents around the respective halves 39a, 39b of the transformer primary winding. The transformer 40 is provided with a secondary winding 43 having a radio-frequency by-pass condenser 44 connected in parallel therewith, the secondary winding being connected in the input circuit of the audio-frequency amplifier 18 to apply thereto the modulation components of the carrier signal.

The frequency-selective or transfer characteristics of the impedance networks 27 and 28 are graphically represented in Fig. 2a. The network 27, which has a frequency-response characteristic as represented by curve d, is proportioned to have a major peak slightly above the upper edge of the range of frequency deviation f' , f'' of the intermediate-frequency carrier sig-

nal and a minor peak below the lower edge. The series-tuned shunt trap circuit 31, 32 of this network is resonant at a frequency f_1 within such range but below the mid-frequency f_0 thereof. Similarly, the network 28, which has a frequency-response characteristic as represented by curve e , is proportioned to have a major peak at a frequency slightly below the lower edge of the range of frequency deviation and a minor peak above the upper edge. The series-tuned circuit 35, 36 is resonant at a frequency f_2 within such range but above the mid-frequency f_0 thereof, the frequencies f_1 and f_2 being equidistant from the mid-frequency f_0 . The resistors 23, 24 are effective to improve the linearity of each characteristic d , e within the range of frequency deviation $f'-f''$ by slightly rounding the peaks. These characteristics have opposite slopes over the mid-frequency range f_1-f_2 or central portion of the deviation range, but their slopes are in the same sense over the end portions f_1-f' and f_2-f'' of the range, the slopes in the latter case being both equal and in the same sense. Hence, the frequency-transfer characteristics of the impedance networks 27 and 28 may be said to be of the same type but sloping in opposite senses with frequency over a smaller frequency range lying within and symmetrically positioned with respect to the mean frequency of the range of frequency deviation of the carrier signals applied thereto, the networks individually having minimum responses at opposite edges of such smaller frequency range.

It may be noted at this point that the curves of Fig. 2a represent only the amplitudes of the outputs of networks 27 and 28 with frequency and neglect the polarity of the output. When the polarity of the output is additionally considered, it is well known in the art that the output of the network 27, for example, has positive and negative polarities over individual portions $f'-f_1$ and f_1-f'' of the frequency-deviation range $f'-f''$, for example, the output may be considered to have positive polarity over the portion f_1-f'' and negative polarity over the portion $f'-f_1$. Thus, if the curves of Fig. 2a also took into account the polarity of the output, curve d would have the same slope over the frequency range $f'-f''$ and the portion of the curve over this range would be a straight line. Similarly, curve c should have the same slope over the frequency range $f'-f''$ and would be a straight line throughout this range. Consequently, the input-output characteristics of the networks 27 and 28 are said to follow a substantially linear relation with frequency over the range of frequency deviation of the carrier signal applied thereto.

The transfer characteristic of the detector system at the output of the rectifiers 37 and 38 of the rectifier stage 17 is represented in Fig. 2b by curves g and h , respectively, these characteristics being curved and varying substantially in accordance with a square-law relation over the range of signal frequencies applied to the detector system from the networks 27, 28. The characteristics are similar and have equal and opposite slopes at the mid-frequency f_0 of the deviation range and like but unequal slopes over the end portions f_1-f' and f_2-f'' of the range.

In considering the operation of the circuit just described, an intermediate-frequency carrier signal is applied to the input of the intermediate-frequency amplifier 15 and there is developed across the load resistors 23, 24 in the output circuit thereof carrier-signal potentials of equal

magnitude but opposite phase. These carrier-signal potentials are applied to the frequency-selective networks 27 and 28 which superimpose on the frequency deviations of the carrier signal the proportional amplitude variations in accordance with their frequency-selective characteristics, Fig. 2a. The outputs of the networks 27, 28 are applied to the respective rectifiers 37, 38, which detect the resulting amplitude modulations of the carrier signals, the rectification occurring in each tube in accordance with its square-law transfer characteristic to provide detector outputs as represented in Fig. 2b. Curves g and h are parabolic over the range of linearity of curves e and d . The outputs of the detectors are differentially combined by the transformer 40 to derive a combined output which varies substantially linearly over the range of frequency deviation of the carrier signal, as represented by the curve k of Fig. 2c, the curvature of the two parabolic-shaped characteristics cancelling out in the combined output of the detector system. It can be shown mathematically that the difference of two parabolas having their axis of ordinates parallel to, but displaced from, one another is a linear function. Thus, the curve k of Fig. 2c is linear over the entire range of linearity of the curves d and e of Fig. 2a and its linearity is quite independent of the separation of the points of minimum response f_1 and f_2 of the latter curves which determine only the displacement of the axes of ordinates of the parabolic curves g and h of Fig. 2b and thereby the slope of curve k .

The differentially combined outputs of the frequency-selective stage 16 and the rectifier stage 17 thus faithfully reproduce the wave form of the frequency-modulation components. During intervals when the carrier signal is unmodulated, the frequency of the carrier is at the mid-frequency f_0 of the range of frequency deviation, so amplitude fluctuations, such as might be caused by noise disturbances, tend to cancel out in the balanced output circuits of the rectifier stage 17. The modulation components appearing in the secondary winding 43 of the transformer 40 are applied to the input circuit of the audio-frequency amplifier 18 and, after amplification therein, are translated by the sound reproducer 19.

An amplitude-limiting system may be provided, if desired, at a point between the intermediate-frequency amplifier 14 and the amplifier 15. In this event, the amplifier 15 is biased to operate in normal manner without limiting action.

The modification of the invention represented in Fig. 3 differs from that of Fig. 1 in that the frequency-selective stage 16a includes two frequency-responsive units 52, 54, each of which includes impedance networks similar to those of unit 16 of Fig. 1, whereby each of the units 52, 54 has frequency-transfer characteristics following substantially a linear relation, as represented in Fig. 2a. The frequency-responsive units 52 and 54 are connected in tandem by an intervening unit 53 comprising a coupling amplifier similar to the amplifier 15. One impedance network of unit 52 and a corresponding impedance network of unit 54 together comprise one of a pair of impedance networks of the frequency-selective stage 16a, each such pair of networks having an over-all transfer characteristic following substantially a square-law relation, not graphically shown but similar to that of the detector transfer characteristics graphically represented by the

curves of Fig. 2b. The amplifier 15 may be biased to operate with limiting action, if desired, but the amplifier of unit 53 must be biased to operate on a linear portion of its characteristic curve since otherwise it would destroy the selective characteristics of the preceding frequency-responsive unit 52. Connected to the output of the frequency-selective stage 16a is a rectifier stage 45 comprising a pair of diode rectifiers 46, 47, connected with opposing polarity, and respective diode load resistors 48, 49. The outputs of the rectifiers 46, 47 are averaged by a pair of serially-connected resistors 50, 51 connected across the load resistors 48, 49 and the demodulation components of the carrier signal appear between the junction of the resistors 50, 51 and the junction of the resistors 48, 49, the output being the average of the unidirectional potentials developed with opposing polarities across the diode load resistors 48, 49. The transfer characteristic of the rectifier stage 45 follows substantially a linear relation over the range of frequencies of the carrier signal applied to the detector system. The transfer characteristic of the detector system at the output of each rectifier 46, 47 is thus as represented by curves *g* and *h* of Fig. 2b, and the output of the frequency detector system, comprising the frequency-selective stage 16a, and the rectifier stage 45, is linear over the range of frequency deviation of the carrier signal, as represented by the curve *k* of Fig. 2c, whereby the wave form of the modulation components of the carrier signal is faithfully reproduced.

It will be evident from the foregoing description of the invention that a carrier-signal receiver embodying the invention is capable of satisfactory operation over a very wide range of frequency modulation, such as the range $f' - f''$ of Fig. 2a, and is, therefore, not limited to the comparatively narrow frequency range of the prior frequency detectors which lies between the frequencies of minimum response f_1, f_2 of the frequency-selective networks of the detector system. The output of the frequency detector system of the invention is proportional to the separation of the frequencies f_1, f_2 of minimum response, so that it is not desirable to have these points of minimum response too close together. On the other hand, the rectified output of the detector system in the center of the band of frequency deviation, which output has to be cancelled in the differential output circuit of the detector, is proportional to the square of the frequency separation of the points of minimum frequency response of f_1, f_2 , so that it becomes desirable to have these points not too greatly separated. As a compromise, the points of minimum frequency response f_1, f_2 should be separated by an amount approximately equal to the normal range of frequency deviation of the carrier signal. This separation may, however, be slightly greater or slightly less without introducing distortion. In any event, the separation of the minimum response f_1, f_2 is not critical insofar as the linearity of the detector output characteristic is concerned, the linearity being simply the result of differentially combining detector output characteristics which have similar parabolic form over the linear portions of the individual impedance network frequency-transfer characteristics.

While there have been described what are at present considered to be the preferred embodiments of this invention, it will be obvious to those skilled in the art that various changes and

modifications may be made therein without departing from the invention, and it is, therefore, aimed in the appended claims to cover all such changes and modifications as fall within the true spirit and scope of the invention.

What is claimed is:

1. A carrier-signal frequency detector system comprising, a frequency-selective stage responsive over a predetermined range of frequency deviation of a carrier signal applied thereto and including a pair of impedance networks having predetermined frequency-transfer characteristics of the same type but sloping in opposite senses with frequency over a smaller frequency range lying within and symmetrically positioned with respect to the mean frequency of said predetermined range, said networks individually having minimum responses at opposite edges of said smaller frequency range, a rectifier stage including a pair of rectifiers individually coupled to said impedance networks, said rectifiers having similar predetermined input-output transfer characteristics, the transfer characteristic of one of said stages following a substantially square-law relation and that of the other of said stages following a substantially linear relation, and an output circuit including means for differentially combining the outputs of said rectifiers to derive an output having substantially linear variation with frequency over a range of frequency deviation including said predetermined range.

2. A carrier-signal frequency detector system comprising, a frequency-selective stage including a pair of impedance networks having predetermined frequency-transfer characteristics of the same type but sloping in opposite senses with frequency over the central portion and sloping in the same sense with frequency over the end portions of a predetermined range of frequency deviation of a carrier signal applied thereto, a rectifier stage including a pair of rectifiers individually coupled to said impedance networks, said rectifiers having similar predetermined input-output transfer characteristics, the transfer characteristic of one of said stages following substantially a square-law relation and that of the other of said stages following substantially a linear relation, and an output circuit including means for differentially combining the outputs of said rectifiers to derive an output having substantially linear variation with frequency over a range of frequency deviation including said range.

3. A carrier-signal frequency detector system comprising, a frequency-selective stage responsive over a predetermined range of frequency deviation of a carrier signal applied thereto and including a pair of impedance networks having similar frequency-transfer characteristics substantially linear but sloping in opposite senses with frequency over a smaller frequency range lying within and symmetrically positioned with respect to the mean frequency of said predetermined range, said networks individually having minimum responses at opposite edges of said smaller frequency range, a rectifier stage including a pair of rectifiers individually coupled to said impedance networks, said rectifiers having similar substantially square-law input-output transfer characteristics, and an output circuit including means for differentially combining the outputs of said rectifiers to derive an output having substantially linear variation with frequency over a range of frequency deviation including said predetermined range.

4. A carrier-signal frequency detector system comprising, a frequency-selective stage responsive over a predetermined range of frequency deviation of a carrier signal applied thereto and including a pair of impedance networks having similar substantially square-law frequency-transfer characteristics but sloping in opposite senses with frequency over a smaller frequency range lying within and symmetrically positioned with respect to the mean frequency of said predetermined range, a rectifier stage including a pair of rectifiers individually coupled to said impedance networks, said rectifiers having similar substantially linear input-output transfer characteristics, and an output circuit including means for differentially combining the outputs of said rectifiers to derive an output having substantially linear variation with frequency over a range of frequency deviation including said predetermined range.

5. A carrier-signal frequency detector system comprising, a frequency-selective stage including a pair of impedance networks each individually tuned to have maximum responses at opposite ends of a predetermined range of frequency deviation of a carrier signal applied thereto and said impedance networks each having a minimum response at respective opposite ends of an intermediate smaller range of frequencies symmetrically positioned about the mid-frequency of said range, whereby the frequency-transfer characteristics of said networks slope in opposite senses over said intermediate range of frequencies, a rectifier stage including a pair of rectifiers individually coupled to said impedance networks, said rectifiers having similar predetermined input-output transfer characteristics, the transfer characteristic of one of said stages following substantially a square-law relation and that of the other of said stages following substantially a linear relation, and an output circuit including means for differentially combining the outputs of said rectifiers to derive an output having substantially linear variation with frequency over a range of frequency deviation including said predetermined range.

6. A carrier-signal frequency detector system comprising, a frequency-selective stage including a pair of impedance networks each having a shunt-tuned circuit and a series-tuned shunt trap circuit so proportioned that each network has a major frequency-response peak on one edge and a minor response peak on the opposite edge of a range of frequency deviation of a carrier signal applied thereto and a point of minimum

frequency response intermediate said range, the point of minimum response being displaced from the mean frequency of said range on the side thereof opposite the major response peak of the individual network, a rectifier stage including a pair of rectifiers individually coupled to said impedance networks, said rectifiers having similar substantially square-law input-output transfer characteristics, and an output circuit including means for differentially combining the outputs of said rectifiers to derive an output having substantially linear variation with frequency over a range of frequency deviation including said range.

7. A carrier-signal frequency detector system comprising, a frequency-selective stage responsive over a predetermined range of frequency deviation of a carrier signal applied thereto and including a pair of impedance networks having similar frequency-transfer characteristics following substantially a linear relation but sloping in opposite senses with frequency over a smaller frequency range lying within and symmetrically positioned with respect to the mean frequency of said predetermined range, said networks individually having minimum responses at opposite edges of said smaller frequency range, a rectifier stage including a pair of vacuum tubes individually coupled to said impedance networks, said vacuum tubes being biased near cutoff to provide similar substantially square-law input-output transfer characteristics, and an output circuit including means for differentially combining the outputs of said rectifiers to derive an output varying substantially linearly with frequency over a range of frequency deviation including said predetermined range.

8. A carrier-signal frequency detector system comprising, a frequency-selective stage including a pair of impedance networks having similar predetermined frequency-transfer characteristics following substantially a square-law relation over a predetermined range of frequency deviation of a carrier signal applied thereto, a rectifier stage including a pair of diode rectifiers individually coupled to said impedance networks, said diode rectifiers having similar substantially linear input-output transfer characteristics, and an output circuit including means for differentially combining the outputs of said rectifiers to derive an output varying substantially linearly with frequency over a range of frequency deviation including said range.
